BURTON S. AIKMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN

CAR-WASHING SYSTEM

Application filed May 26, 1927. Serial No. 194,283.

My invention relates to washing systems such as are employed for washing automobiles with a fluid jet comprising a spray of water projected and broken up by compressed air. While I shall describe my invention as embodied in such a car washing system, I do not intend to be limited to the particular use to which the same is put.

According to the present invention, I provide a source of air under pressure and a source of water under pressure, and I provide means for maintaining an accurate relation of the pressure so that a suitable fine spray of water moving at high velocity may be secured for wetting the surface to be cleaned and for flushing the surface with the required force to remove all grit, sand, dirt and the like, and leave the surface completely clean and unclouded.

A high velocity jet of water alone is not suitable. If there is sand or grit on the surface to be cleaned, a high velocity jet of solid water will tend to cut the finish. Also, too much water is wasted, since the water does not have the spreading power nor the required area, and if it is attempted to break the water jet by projecting the same through a fine nozzle, such as a rose nozzle, the openings will be quickly clogged by any minor impurities which may be in the water. Furthermore, it appears that the presence of the stream of air in the spray has the highly beneficial effect in driving the film of water along the surface in a manner tending constantly to clean the same. That is to say, in the spray which is produced by a nozzle of this character, a separate drop of water arrives on a given area and the surface is wetted and immediately thereafter the film of water which is thus deposited on the surface is moved laterally by the wiping action of the stream of air. This is followed by the wetting of the same surface with a succeeding drop and again the wiping action of the air. It will be seen, therefore, that the spray produced by a system of this kind has the capability of cleaning a surface very rapidly and effectively.

The success of the operation depends upon breaking the water up into drops and spread-

ing the spray from the nozzle to cover a relatively great area. The secret of successful operation of the nozzle is the maintenance of a uniform pressure relation between the water and the air streams. Preferably, the air and water are maintained at substantially equal pressures so that they tend to travel together without separation and so that after the orifices and passages through which these fluids travel are once fixed, operation of the system will give substantially uniform results under all conditions.

Preferably, in accordance with my invention, the water pressure is controlled by the air pressure. It is, however, within the spirit of my invention to control the air pressure in accordance with the water pressure, so that a uniform relation is maintained between them.

Where the compressed air is supplied from a tank or reservoir charged by a compressor, there is a tendency for the pressure of the air to fluctuate between certain limits, particularly in a small installation.

Obviously, without departing from my invention, the air may be compressed to a suitable value above the required pressure, even with wide fluctuations, and a reducing valve employed between the reservoir and the line to smooth out, as much as possible, the fluctuations of air pressure. On a relatively large system there is a tendency to keep the pressure substantially uniform, but the mere maintenance of the air pressure alone is not all that is required. There must be an inter-control between the two fluids so that for best results the pressure ratio between them should be uniform.

I prefer to let the air pressure vary within reasonable limits, and cause it to exert a control over the water pressure. A source of water supply is provided which is capable of delivering water at a pressure not substantially lower than the maximum pressure of air delivered, and by a suitable valve under the control of the air pressure the delivery pressure of the water is varied to keep a definite relation, preferably equality, with the air pressure. This relation, obviously, may be reversed.

193

The pressure regulating valve, for regulating the delivery pressure of the water, is placed in the water line at some suitable point which may be varied to suit the particular requirements of the water supply means.

I wish to point out further that, while in the preferred form of the invention I have shown a car washing system, it is to be understood that the intercontrol between air and liquid which my invention provides may be useful in other spraying systems, as, for example, in applying liquid coatings to surfaces, as in paint spraying, although the requirements are different, as will be recognized by those skilled in the art, since in the paint spray the usual condition which is required is an exceedingly fine mist of the liquid as distinguished from the relatively coarse spray which I employ in car washing.

Now, in order to acquaint those skilled in the art with the manner of constructing and operating a system embodying my invention, I shall describe in connection with the accompanying drawings a specific embodiment of the same.

Fig. 1 is a diagram, showing certain parts in section, of a system embodying my invention;

Fig. 2 is a similar diagram of a modification; and

Fig. 3 is a fragmentary sectional view of a modified form of gun or spray nozzle.

Referring now to the system shown in Fig. 1, the tank or receiver 1 contains air under suitable pressure of the order of 100 pounds per square inch. This tank may be charged by a suitable compressor under automatic control. Any other suitable source of air supply may be provided. In an embodiment of the invention which I have constructed, I maintain approximately 115 pounds per square inch air pressure. A source of liquid supply 2 is shown, in this case the city water main. However, the pressure in the city water main is usually too low to operate satisfactorily in a system of this character. I provide, therefore, a centrifugal pump 3 which, in the present instance, is of the multistage type, driven by an electric motor 4 constantly operating so long as the system is in use. The compressed air from the tank 1 and the water from the main 2 regulated in a manner which I shall describe later, are introduced into the mixing chamber 5 which is preferably placed vertically above the point of use of the spray gun 6. The chamber 5 has an inlet at 7 through which projects a nozzle 8 having a suitably restricted opening 9 in the lower end of the same. This nozzle is threaded into a socket 10 formed in the wall of the chamber 5, and it, in turn, provides a pipe socket into which a nipple 11 is threaded, this nipple in turn being connected through the T 12 and pipe line 13 to the air tank 1. The nozzle 8 con-

tains a screen for intercepting solid particles, oil or other impurities, and this screen 14 is loosely seated inside of the nozzle 8. The chamber 5 is preferably of a generally spherical shape and it has an outlet for air and liquid at the bottom. The outlet connection comprises a pipe 15 threaded into a suitable socket 16 and extending substantially vertically downward through a gate shut-off valve 17 having the controlling handle 18 to a flexible hose portion 19 joined to the gun 6. The gun 6 has a suitable handle portion 20 by which the same may be manipulated. The gun 6 has a restricted outlet, as indicated at 21, through which the air and water are projected to form a coarse high velocity spray which spreads out laterally to cover a relatively large area, as compared with a solid stream which might be projected through the same outlet. The hose and gun should be arranged to provide as short a lateral run as possible, so as to prevent the effect known as "slugging", namely, the separation of the water into slugs, so that the operation of the gun would be erratic.

Liquid is introduced into the mixing chamber 5 through a lateral connection comprising the pipe connection 23 leading from the discharge or delivery outlet 24 of the pump 3. A suitable run of pipe from the outlet 24 of the pump 3 to the inlet connection 23 of the chamber 5 is formed of the usual iron piping. A pressure gage 26 is provided for indicating the delivery pressure of the water entering the chamber 5. The inlet side of the pump 3 is connected through a pipe 28 to the water main 2 through a pressure regulating valve 29. This pressure regulating valve 29 controls the admission of water from the main 2 to the intake of the pump 3. It comprises a valve body 30 mounted on the stem 31, which extends up through a guide and packing to a plunger or plate member 32 to which it is connected. The valve 30 on its lower side has a guiding stem 33 guided in a spring cage 34 containing the spring 35. The spring 35 tends to raise the valve 30 to its seat. The plate or piston 32 engages a diaphragm 36 which is stretched across the diaphragm chamber 37 and clamped at 38 between the flanges of the cover member 37 and the body 39. The space above the diaphragm 36 is connected by a pipe 40 to the T 12 where the compressed air is delivered to the nozzle member 8. A pressure gauge 27 indicates the pressure of the air imposed upon the nozzle 8 and operating upon the diaphragm 36. The main 2 normally carries pressure and it operates on the outer face of the valve 30 tending to close the same together with the action of the spring 35. The suction of the pump on the opposite side of the valve tends to draw the liquid to the extent permitted by the

opening of the valve 30 and discharge the same through the pipe 25, connection 23, to the mixing chamber 5. The spring 35 is so graduated to the normal air pressure and 5 diaphragm area as to regulate the water delivery to be substantially equal to the air delivery pressure. If the pressure of the air is slightly above normal, the plunger 36 and valve 30 will be depressed, and a 10 larger amount of water permitted to enter the pump 3, with a resulting increase in the delivery pressure in the water conduit 25.

Assume that the parts are in the position shown in Fig. 1 and that the motor 4 and 15 pump 3 are in operation, as soon as pressure is applied to the diaphragm 36 the valve 30 will be opened to a degree permitting the building up of pressure on the delivery side of the pump equal to the air pressure. Air 20 passes down through the nozzle 8 and is discharged at the opening 9 towards the outlet to the pipe 15. Water enters by the connection 23 and it tends to spray into the chamber 5 and whirl rotarly about the outlet 25 opening 15 in a substantially uniform manner, the two fluids mixing so as to break up the solid stream of water and dropping through the pipe 15 and hose 19 and escaping simultaneously at the constricted 30 opening 21 in the gun 6. The result is a high velocity spray of drops of water and air which wet and scour the surface to be cleaned with great effectiveness.

It is customary to operate two guns, one 35 on each side of the car being washed where washing operation is carried on in a large scale. Where two or more guns are to be operated from a system such as shown in Fig. 1, it is preferable that the delivery 40 pressure of the water be impressed upon the bottom of the diaphragm 36 so that the position of the valve 30 will be determined by a comparison of the pressure of the two fluids as they are delivered to the mixing 45 chambers.

While I have shown a centrifugal pump for providing the necessary water pressure, it is to be understood that any suitable means 50 for providing the desired pressure and delivery of water may be substituted, as, for example, a positive displacement pump of the reciprocating piston type.

In Fig. 2 I have indicated a system in which a reciprocating piston type of pump is employed for furnishing the necessary liquid under pressure. In this case I provide a pump 45 of the well known reciprocating steam pump type in which the motor cylinder 46 is supplied with water under pressure 55 from the city mains through the supply pipe 41 and the pump cylinder 47 is connected to the discharge pipe 25 leading through the pressure regulating valve 29' to the mixing chamber 5. The pump 45 in this case is a booster, operated by the pressure of the city

mains for raising the pressure of water delivered from the city mains to the desired delivery pressure. The supply pipe 41 leading from the city mains 2 has two branches 48 and 49 leading to the motor and pump cylinder, respectively. The water which is employed in the motor cylinder 46 is discharged through an exhaust pipe 50 to the sewer connection. The water which is drawn through the pipe 49 into the cylinder 47 is raised to the desired pressure and, under the control of the regulating valve 29', is delivered to the chamber 5 at a pressure substantially equal to the air pressure. In this case the bottom side of the diaphragm is subjected to the pressure existing in the pipe 51, which is on the delivery side of the valve 29'. Provision for introducing the pressure below the diaphragm 36 is made by fluting the stem 31 to permit the pressure in the pipe 51 to act upon the bottom side of the diaphragm. The diaphragm is therefore balanced between the air pressure and the pressure of the water in the delivery pipe 51, the valve 30 being held normally closed by the pressure of the spring 35. The pressure of the spring 35 is relatively light and may be adjusted to any desired value. So long as the system is in operation the valve 30 is held away from its seat by the slight preponderance of air pressure required to oppose the spring 35.

In other respects, the system shown in Fig. 2 is the same as described and disclosed in connection with Fig. 1.

Absolute equality between the air and water pressure is not essential to the practice of the invention, but it is desirable that the pressures, if they vary, should vary together, so that the effectiveness of the spray at the nozzle of the gun will be as great as is permissible with the pressures available.

While I have shown in Fig. 2 the valve 29' inserted in the water delivery pipe for regulating the water flow in accordance with variations of air pressure, it is to be understood that it is within my invention to insert the said valve in the air delivery line 13 and to control the same in accordance with variations of water pressure if so desired.

Furthermore, I do not intend to be limited to the specific mixing and delivery mechanism which I have described, although for this service the apparatus described has operated satisfactorily. For example, as shown in Fig. 3, I may provide the mixing chamber 5' within the nozzle 21' and lead the water and the air in by concentric pipes 53 and 54, respectively, the mixture of air and water leaving the gun 6' through the orifice or nozzle 21' as a blast of air carrying drops of water. Where the form of mixing chamber shown in Fig. 3 is employed, the pipes 53 and 54 may run horizontally any desired distance without danger of slugging, since the

5 mixture is formed immediately adjacent the restricted outlet 21', whereas, in the form shown in Figs. 1 and 2, it is desirable not to run the mixture of air and water any appreciable extent horizontally where the same has a tendency to separate the air from the water and result in so-called "slugging," which is alternate ejections of a slug of water and a pocket of air.

10 I do not intend to be limited to the details shown and described.

I claim:

15 In a car washing system, a spray nozzle for air and liquid having a restricted opening, a source of liquid, a source of air under pressure, a substantially spherical large volume mixing chamber, an outlet port leading from said chamber, an air nozzle located in said chamber diametrically opposite from 20 said port, a water inlet port located midway between said outlet port and air nozzle, a hose having a cross-section area substantially equal to the area of said outlet port for connecting said spraying nozzle to said mixing 25 chamber, a pump supplied with liquid from said source for increasing the pressure of the liquid and delivering it to said mixing chamber where it is thoroughly mixed with air blown from said air nozzle, and the mixture 30 discharged from said chamber through said outlet port, hose and spraying nozzle, and a throttle valve in the intake of said pump opened by the pressure of the air proportionately to that pressure to thereby keep the 35 pressure of the liquid delivered by the pump to the mixing chamber at a predetermined value with respect to the pressure of the air delivered thereto.

40 In witness whereof, I hereunto subscribe my name this 21st day of May, 1927.

BURTON S. AIKMAN.
